UNITED STATES PATENT OFFICE.

MARTIN L. WILLIAMS, OF SOUTH BEND, INDIANA, ASSIGNOR, BY MESNE ASSIGNMENTS, TO GILLETTE MOTORS COMPANY, OF CHICAGO, ILLINOIS, A CORPORATION OF WEST VIRGINIA.

MOTOR-CAR MANIFOLD.

1,238,862.

Specification of Letters Patent. Patented Sept. 4, 1917.

Application filed August 4, 1913, Serial No. 782,812. Renewed February 8, 1917. Serial No. 147,492.

To all whom it may concern:

Be it known that I, MARTIN L. WILLIAMS, a citizen of the United States, residing in the city of South Bend, county of St. Joseph, 5 and State of Indiana, have invented certain new and useful Improvements in Motor-Car Manifolds, of which the following is a specification.

This invention relates to improvements in 10 motor car manifolds, and has among its salient objects to provide a construction in which the heat from the exhaust is utilized to vaporize the fuel in the inlet manifold, whereby the fresh fuel is vaporized in the 15 inlet manifold instead of in the carbureter; to provide a construction in which the fresh fuel entering the inlet manifold is exposed to a maximum vaporizing surface heated by the exhaust gases before it enters the cylinders; to provide a construction in which the relatively cool fuel and air are first mixed in the 20 carbureter and then completely vaporized in the inlet manifold, just before the gases enter the cylinders; to provide a construction which is particularly adapted for use with 25 standard types of motor cars and automobiles now on the market, and without necessitating a reconstruction or re-arrangement of the engines now in use on motor cars; to provide a construction in which the exhaust 30 gases by reason of their heat units being utilized as aforesaid are delivered from the exhaust manifolds to a relatively low temperature; to provide a construction in which the inlet and exhaust manifolds are prefer- 35 ably made in a single casting; to provide a construction which permits of the use of poor and cheaper fuel than is now practical in the present constructions, and at the same time obtains a large efficiency, and in general to provide an improved construction of 40 the character referred to.

The invention consists in the matters hereinafter described and more particularly pointed out in the appended claims.

50 In the drawings—

Figure 1 is a side elevation of a four cylinder gas engine equipped with my invention;

Fig. 2 is a top plan view of the same;

55 Fig. 3 is a vertical view, partly in side ele-

vation and partly in section, showing in addition the crank casing;

Fig. 4 is a vertical cross sectional view taken on lines 4—4 of Fig. 1 and looking in the direction of the arrows;

Fig. 5 is a vertical sectional view taken on lines 5—5 of Fig. 1 and looking in the direction of the arrows.

Referring to the drawings—

1 designates the four cylinders of a gas engine, 2 the crank case, 3 the crank shaft, 4 the pistons and 5 the piston rods. 6 designates the valve stems of the inlet valves and 7 the valve stems of the exhaust valves. 8 designates the spark plugs, 9 the priming cups. The foregoing is all of well known construction, and need not be further described in detail.

The essence of the present invention consists in the manifold construction proper. 75 It comprises an inlet manifold 10, and exhaust manifold 11, both of which are formed as a single casting, and extend longitudinally along side of each other, being divided by a partition wall 12. The exhaust manifold 11 communicates directly with each cylinder by means of a throat or conduit 13, formed integral with the manifold. It will be understood that there is one of these throats or conduits 13 for each of the cylinders. The inlet manifold 10 communicates with the inlet ports of the cylinders by means of throats or pipes 14. It is to be noted that the conduits for the inlet and exhaust manifolds are alternately arranged 80 and lie in the same horizontal planes. They are formed by staggering the partition wall 12 in the manner shown in the drawings. The intake manifold is connected to the carbureter (not shown) by means of an inlet or feed pipe 15. The manifold casting is secured to the cylinders as follows;—on the cylinders are studs 16 which go through apertured bosses or lugs 17 on the manifold, and are secured thereon by nuts 18. 85

The operation of the manifold is as follows;—assuming that the engine is running, the relatively cool fuel and air after being mixed in the carbureter in the usual manner pass through the inlet pipe 15 into the inlet 90 manifold 10. This fresh charge passing through the inlet manifold is heated by the hot outgoing exhaust gases, and the radiation of the heat units from the latter gases completely vaporizes the fresh charge of 100 105 110

fuel. It is to be noted that this vaporization takes place substantially at the points where the vaporized charge enters the cylinders. The exhaust gases are of course, cooled by the incoming fresh gases and discharge from the exhaust manifold at relatively low temperatures.

The invention is not limited to the details of construction shown, except as set forth in 10 the appended claims.

I claim as my invention:

1. In a gas engine, the combination with a plurality of cylinders, of a manifold construction therefor comprising inlet and exhaust manifolds lying along side of each other and divided by a partition wall, conduits leading alternately from the intake and exhaust manifolds to the inlet and exhaust ports of the cylinders, lying substantially in the same horizontal planes and formed by staggering said partition wall.

2. In a gas engine, the combination with a plurality of cylinders, of a manifold construction therefor comprising inlet and exhaust manifolds lying alongside of one another and divided by a single partition wall, conduits arranged in pairs adjacent each other and leading alternately from the intake and exhaust manifolds to the inlet and exhaust ports of the cylinders, said conduits lying in the same horizontal planes and formed by staggering the single partition wall.

3. In a gas engine, the combination with a plurality of cylinders, of a manifold construction therefor, comprising inlet and exhaust manifolds lying alongside of one another and divided by a single partition wall, conduits leading to the intake manifold and conduits leading to the exhaust manifold, 40 said conduits being formed by staggering the single partition wall.

4. The combination with an internal combustion engine provided with a plurality of cylinders having valve controlled inlet and exhaust ports, of a manifold associated with the cylinders and arranged at one side of the same and comprising elongated inlet and exhaust chambers lying along side of each other, the major portions of their walls being non-opposed and exposed to the atmosphere and their minor portions throughout the major portions of their length being in close-juxta-position, whereby heat will be transferred from the exhaust to the mixture 55 within the inlet chamber, said manifold having a plurality of inlets and outlets leading from the non-opposed sides of said chambers, said inlets and outlets being substantially in alinement and coöperating with the 60 valve controlled inlet and exhaust ports of the engine cylinders.

MARTIN L. WILLIAMS.
